DESK AND SEAT COMBINATION

Ernest J. Kump, Jr., San Francisco, Calif.

Application May 2, 1949, Serial No. 2,372

Term of patent 14 years

(Cl. D33—11)

To all whom it may concern:

Be it known that I, Ernest J. Kump, Jr., a citizen of the United States, residing at San Francisco, in the county of San Francisco and State of California, have invented a new, original, and ornamental Design for Desk and Seat Combination, of which the following is a specification, reference being had to the accompanying drawing, forming part thereof.

Fig. 1 is a perspective view of a desk and seat combination, showing my new design.

Fig. 2 is a side elevational view of the desk and seat combination.

Fig. 3 is a rear elevational view of the desk and seat combination.

Fig. 4 is a front elevational view of the desk and seat combination.

I claim:

The ornamental design for a desk and seat combination, as shown.

ERNEST J. KUMP, JR.
